(57) **CLAIM**

The ornamental design for a panel interconnectable with similar panels for forming a covering, as shown and described.

DESCRIPTION

FIG. 1 is a top perspective view of a panel interconnectable with similar panels for forming a covering, showing an embodiment of our new design;

FIG. 2 is another top perspective view thereof;

FIG. 3 is a front side view thereof;

FIG. 4 is a rear side view thereof;

FIG. 5 is a left side view thereof;

FIG. 6 is a right side view thereof;

FIG. 7 is a top view thereof; and,

FIG. 8 is a bottom view thereof.

The broken lines showing other components in FIGS. 1-5, 7, and 8, are for illustrative purposes only and form no part of the claimed design.

1 Claim, 6 Drawing Sheets
